INVENTOR

H. Cole

BY *Victor J. Evans*

ATTORNEY

WITNESS:

UNITED STATES PATENT OFFICE.

GEORGE SHELLCROSSLEE, OF CANTON, ILLINOIS.

TOOL.

Application filed April 30, 1923. Serial No. 635,683.

To all whom it may concern:

Be it known that I, GEORGE SHELLCROSSLEE, a citizen of the United States, residing at Canton, in the county of Fulton and 5 State of Illinois, have invented new and useful Improvements in Tools, of which the following is a specification.

The object of this invention is to provide a tool for use by miners in splitting and 10 cutting fuses.

A further object is to provide a tool of this type which shall include a stationary element formed in longitudinal sections and a knife and a holder adapted to be pivotally 15 mounted between the sections and to engage and split a fuse inserted longitudinally of the knife, or to cut a fuse inserted transversely of the knife.

A further object is to avoid accidents frequently resulting from the operation of 20 splitting fuses by hand, and to provide for making a clean split without the loss of powder in the split portions.

A still further object is to provide a device 25 in which each section of a stationary element shall include an offset portion in which the blade or knife is pivoted, said offset portion being provided with longitudinal channels which together form 30 a bore for receiving the end of the fuse to be split, transverse notches being also provided for receiving a fuse to be cut transversely.

With the foregoing and other objects in 35 view, the invention consists in the novel construction and arrangement of elements described and claimed, it being understood that modifications may be made within the scope of the claim without departing from 40 the spirit of the invention.

In the drawings, Figure 1 shows the device in side elevation; Figure 2 is a longitudinal section, with the cutting element and one side member in elevation; Figure 45 3 is a section on line 3-3 of Figure 1.

The stationary element of the device includes a pair of elements 10 and 11 which together form a handle, each of these elements being formed with a head 13 offset 50 from the longitudinal axis of the handle,

in order to provide for the proper mounting of the blade and blade holder.

The elements 10 and 11 are flat on the major portion of the inner surface, and are partly round on the outer surface, being 55 retained in parallel relation by screws 14 and 15. Each head is provided with a half round groove, such as 16, the grooves together forming a bore for the accommodation of the fuse to be split. The heads are 60 further provided with transverse notches 18 for receiving a fuse to be cut transversely to the proper length.

A blade 20, also termed a knife, is mounted rigidly in a blade holder constituting a 65 handle and formed of two metallic strips 22, 23, riveted together. The blade holder is provided with apertures in each element thereof, and the blade is provided with a registering aperture for the accommodation 70 of a pivot member 24. The pivot also passes through apertures 25 in each section of the stationary element. The relation of the cutting edge and the angle of the bore receiving the fuse is such that the best results are secured, a gradual downward cut being provided for and the angle of the cutting edge with reference to the bore being more acute during the latter part of the stroke than at the beginning thereof. The 80 screw limits the movement of the blade toward the open position.

What is claimed is:—

A device of the class described comprising 85 a stationary member formed in longitudinal sections and each including a head offset therefrom, the offset portions having channels therein adapted to form a bore for the fuse, a blade holder operating between said sections, a blade mounted in the holder 90 and adapted to be moved to position for causing said blade to pass longitudinally through the bore, said blade holder including parallel metallic strips having registering apertures and the blade also having an 95 aperture, and a pivot member passing through all of said apertures and through the heads.

In testimony whereof I affix my signature.
GEORGE SHELLCROSSLEE.
